UNITED STATES PATENT OFFICE.

HUGO MOCK, OF NEW BRIGHTON, NEW YORK.

FIRELESS COOKER.

1,160,939.

Specification of Letters Patent. Patented Nov. 16, 1915.

Application filed March 12, 1915. Serial No. 14,026.

To all whom it may concern:

Be it known that I, HUGO MOCK, a citizen of the United States of America, residing at New Brighton, in the county of Richmond and State of New York, have invented certain new and useful Improvements in Fireless Cookers; and I do hereby declare the following to be a full, clear, and exact description of the invention such as will enable others skilled in the art to which it appertains to make and use the same.

This invention is designed to provide a fireless cooker without the usual non-conducting metal ordinarily associated with these appliances and is intended to provide a fireless cooker made almost entirely of metal which shall be light in weight, ornamental in appearance and efficient in conduction and radiation of heat from the cooking utensil.

In the drawings, Figure 1 presents a vertical sectional view through the cooker showing the parts assembled, Fig. 2 shows a horizontal section view as on the line 2—2 of Fig. 1, and Fig. 3 shows a similar view as on the line 3—3 of Fig. 1.

Essentially the device consists of a series of concentric bell shaped covers of varying sizes adapted to be superimposed over each other, each bell resting on a base slightly larger than the perimeter of the bell which supports said base A having a depending flange b upon which the bell 1 rests. The bases A are separated from each other by insulating pins C which are preferably made of hard rubber, bone, wood or other heat non-conducting material. The bells as well as the bases upon which they rest are preferably made of aluminum or other light metal capable of taking a high polish. Each of the bells with its appropriate base incloses a certain portion of air which acts as a non-conductor and as both its internal and external surfaces are highly polished, there is little radiation or conduction of heat from one bell to the next inclosing same. As direct conduction of heat from one base to the other is prevented by insulating pins C, a fireless cooker made in this fashion is found as equally efficient as the cookers provided

with the usual non-conducting materials. The larger these bells are made and the more bells that are used, the more efficient will be the fireless cooker on account of inclosing a greater volume of air and on account of 55 having a greater number of successive surfaces to prevent radiation of heat.

Having thus described my invention, what I claim is:—

1. A fireless cooker comprising a series of 60 bell shaped metallic covers of varying sizes superimposed one upon the other, each cover resting on a metallic base slightly larger than its diameter so as to inclose an air space, said covers being separated from each 65 other by non-metallic pins supporting said bases.

2. A fireless cooker comprising a series of bell shaped metallic covers of varying sizes superimposed one upon the other, each cover 70 resting on a metallic base having a depending flange slightly larger than its diameter so as to inclose an air space, said covers being separated from each other by non-metallic pins supporting said bases. 75

3. A fireless cooker comprising a series of one piece bell shaped metallic covers superimposed one upon the other, each cover resting on a metallic base so as to inclose an air zone, said bases being supported by and insulated from each other by non-conducting pins. 80

4. In a fireless cooker, a metallic base adapted to support the cooking vessel, a bell shaped metallic member adapted to cover 85 said vessel, resting on said base and forming an air zone about said vessel and a series of metallic covers and bases of varying sizes arranged concentrically around said vessel so as to form a series of air zones to insulate 90 same, the bases being supported and insulated from each other by non-conducting pins.

In testimony whereof I affix my signature in the presence of two witnesses.

HUGO MOCK.
